(57) **CLAIM**

The ornamental design for a shower head as shown and described.

DESCRIPTION

FIG. 1 is a front elevational view of a shower head showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is an enlarged view of the encircled portion '9' in FIG. 1;

FIG. 10 is an enlarged view of the encircled portion '10' in FIG. 7; and,

FIG. 11 is an enlarged view of the encircled portion '11' in FIG. 8 thereof.

The broken lines shown in the drawings are for the purpose of illustrating portions of the article that form no part of the claimed design.

1 Claim, 11 Drawing Sheets
